CLAIM

The ornamental design for computer display monitor for use in testing electric and electronic circuitry, substantially as shown and described.

DESCRIPTION

FIG. 1 is a front elevational view of a computer display monitor for use in testing electric and electronic circuitry showing our new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is an enlarged fragmentary view of the grill disclosed in FIG. 4-6.

FIG. 1

FIG. 2

FIG.3

FIG.4

FIG. 5

FIG. 6

FIG. 7
